Attorney
J. Stuart Freeman.

UNITED STATES PATENT OFFICE

1,939,828

HOSIERY

Richard H. Oswald, Philadelphia, Pa.

Application September 17, 1930
Serial No. 482,403

1 Claim. (Cl. 66—187)

The object of the invention is to provide improvements in hosiery broadly, but more particularly in the shape of the heel portion, and the method of automatically forming the same in a full fashioned knitting machine.

Heretofore, the wales of each lateral side of the heel portion, after running parallel for a distance, have been made to curve towards a central narrowing, by gradually discontinuing the wales progressively from the center of each side in opposite directions, so that a taper is formed. However, as all of the wales do not terminate in such narrowing, the outermost wales extend to the normally lower end of the heel, and those upon the opposite sides of the heel are secured together by means of a seam, which unites at the rear with the back seam which characterizes full-fashioned hosiery, with the result that an objectionable angular extension or offset is formed. This angular portion, falling as it does beneath the center of the heel of the wearer is most undesirable, as it can seldom be stretched out fully and resultingly folds over and presents a triple thickness of material upon which the wearer must walk.

The object therefore has been to produce a heel portion of a natural shape and to so revise the method of forming the heel portion that it will be free from irregular extensions and in general conforming closely to the shape of the heel of the wearer, and for this purpose to make the proper alterations in the hosiery knitting mechanism and operation of the same.

With these and other objects in mind, the present invention comprises further details of construction and operation, which are fully brought out in the following description, when read in conjunction with the accompanying drawing, in which Fig. 1 is a fragmentary side elevation of an improved piece of hosiery embodying the invention; Fig. 2 is a fragmentary front elevation of a portion of a well-known type of hosiery knitting machine; Fig. 3 is a fragmentary end elevation of another portion of such machine; and Fig. 4 is a front elevation of that portion of the machine shown in Fig. 3.

According to the invention, wales 20 form the improved heel and each side of the heel consists of forward groups or sets 21 and rear groups or sets 22. The wales of sets 21 are in parallel relation throughout, while those wales in the set 22 at their upper portions are parallel with the wales 21 but at their lower portions are arcuate and terminate at the rear-most wale 21 so that a single wale contains the

line of fashioning marks. The rear seam 24 as a result conforms to a substantially true arc and merges into a bottom seam 25 which connects the lower ends of the sets of parallel wales 21.

Referring now to Figs. 2, 3 and 4, these represent portion of a "Reading" full-fashioned knitting machine as illustrated in the July 1929 issue of the Parts catalog of the Textile Machine Works, of Reading, Pennsylvania. Above the usual needle bar 1 are positioned the oppositely movable narrowing rods 2 and 3, to which are fixed the respective narrowing combs 4 and 5 carrying sets of points 4' and 5'. The relative movement of the narrowing rods and the corresponding combs is effected in well-known manner through various mechanical elements (not shown), which are moved intermittently by a ratchet pawl 6 for the forward movement and a second pawl 7 for the backward movement of the narrowing head, said pawls respectively engaging ratchets 8 and 9 having oppositely directed teeth. Both of these ratchets are carried by a common shaft 10, which also carries a lock dial 11 with which engages a retaining latch 12.

In the normal operation of the machine of which these several elements form a part, after the upper portion of the usual heel has been formed with its wales all in parallel relation, the narrowing combs are simultaneously moved inwardly or towards each other two notches, that is, the width of two of their respective points, by engagement of the first pawl 6 with its ratchet 8, after which said combs are simultaneously moved outwardly or away from each other a distance of a single notch or point, by reason of the engagement of the second pawl 7 with its ratchet 9. The movement of this last-named pawl is limited to but one ratchet tooth, or point of the lock dial, by reason of its cut-away portion 14 being of less vertical extent than that shown in Fig. 3, the shape illustrated representing the extent to which the improved mechanism differs from the actual shape of the parts illustrated in the above-named catalog. However, with an increase in the length of said cut-away portion of the second pawl as illustrated, the pawl is permitted to engage a second tooth instead of but one each time it moves downwardly, and thereby cause the combs to move outwardly a distance of two notches or points, or a distance exactly equal to that to which they are previously moved inwardly by the pawl 6.

This difference in shape of the second pawl 7, simple as it may seem, with its resultant effect brings about the production of the heel shape shown in Fig. 1.

5 Having thus described my invention, what I claim and desire to protect by Letters Patent of the United States is:—

10 A knit article of full-fashioned hosiery having a heel composed at each side of a group of wales in parallelism with each other and terminating in a substantially central, longitudinally extending seam at the bottom of the article, and groups

of wales rearwardly of the said first groups of wales completing the heel, said rear groups of wales having their upper portions parallel with each other and with the first groups of wales, and the lower portions of said second groups of wales being substantially arcuate and respectively extending to the single rearmost wale of each of the first-mentioned groups of wales, said rearmost single wales thus containing the lines of fashioning marks.
